ABRAHAM PRESS, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROLLABLE GRID LEAK.

Application filed June 25, 1920. Serial No. 391,648.

This invention relates to wireless telegraphy and particularly to grid-condenser circuits of triodes, and it has, for one of its principal objects, the provision of a control for such condenser circuits.

In the art of wireless telegraphy, it has been found that a condenser, when used in the grid circuit, has had important advantages in amplifying the received signal.

10 In the case of relatively soft tubes, such as those first employed by De Forest, the amount of grid leak required for the condenser was exceedingly small, by virtue of the ionization present in the triode.

15 The prior art shows that, in order to enable such a discharge to take place with hard tubes, where the above ionization is not present, a resistance shunt of from one to ten million ohms has been necessary. A

20 difficulty encountered with such discharge resistances, preferably of the non-reactive type, has been their great fragility and, especially, their inconstancy. The present invention, therefore, contemplates, as one of 25 its features, the provision of a grid-leak controlling means which shall be practicably invariable and, furthermore, one that shall combine, as far as possible, all the soft-tube requirements of the De Forest conductive 30 ionization and still retain the advantages of a hard tube.

35 Other features of my invention will obviously follow from an inspection of the drawings when taken in conjunction with the accompanying description.

Figure 1 is a diagram illustrating a preferred embodiment of my invention in which a soft-tube control is placed across the grid-filament connections of a hard triode.

40 Fig. 2 is a diagram illustrating an alternative form of my invention, wherein the control element is merged with the triode grid.

Figs. 3 and 4 are diagrams illustrating alternative arrangements of hard-tube controls for triode circuits.

45 In the usual receiver circuit, a variable grid condenser 1 is connected, on the one side, to the grid 2 of a triode 3, and, on the other side, to a coupling coil 4. Shunted across the coupling coil 4 is a condenser 5 to co-operate therewith as a part of an canalization which includes the lead 6 attached to the filament 7 of the triode. The filament 7 is excited in the usual manner by means 55 of an adjustable battery connection 8. The

plate 9 of the triode is, moreover, connected through the usual telephone set 10 and battery 11 to the lead or canalization 6. It is also usual to shunt the telephone and its associated battery with a condenser 12.

60 The soft-tube control element 13 of my invention, as shown in Fig. 1, is connected in shunt with the grid-filament circuit of the hard-vacuum type of triode 3. The filament 7' of the grid control is fed by a battery 14, 65 one pole of which is connected to the lead 6, whereas the plate 15 of the control is connected to the grid element 2. In the type of circuit shown in Fig. 1, the two separate functions present in the De Forest type of 70 circuit are separated so that the conduction from the lead 6 to the lead connecting the variable condenser 1 and the grid 2 shall not be affected by the influence of an ionization characteristic with respect to the plate 75 9 of the triode.

As a possible alternative to the arrangement shown in Fig. 1, I provide, in Fig. 2, a triode 3', in which a grid element 2', functioning partially as a hot cathode by means 80 of an exciting battery 14', is provided. Thus, by virtue of the two cathodic elements 2' and 7, the equivalent of an ionization atmosphere will occur within the triode in such manner as to fulfill the requirements of 85 the De Forest soft-vacuum triode.

However, I do not wish it to be understood that my invention is limited, in its more general applications, to a shunting of the hard type of triode by means of an Edison 90 valve having a soft vacuum. Thus, in Figs. 3 and 4, especially, I have shown two possible arrangements whereby a hard-vacuum tube may be made to function very much in the same manner as the grid element 2' acts 95 toward the filament 7 in the triode 3'. By providing a hard type of Edison valve it is found necessary to attach one pole of the exciting battery 14 to the grid 2 of the triode, and the plate 15 of the control to the 100 lead 6. In Fig. 4, in addition, I have provided an adjustable-voltage control 16 in the lead joining the plate 15 with the conductor 6.

In the operation of my invention, it 105 should be noted that the usual type of adjustment with respect to a given frequency of signal should be made without any reference to the grid control. Thereafter, the batteries 14 or 14' are adjusted in order to 110

obtain the right type of ionization effect with respect to the filament 7 of the triode. By this means, it will be found that a very marked improvement in the operation of the 5 entire signalling system will be achieved.

While I have described and illustrated certain embodiments of my invention, it will be apparent to those skilled in the art that various changes, modifications, substitutions, 10 additions and omissions may be made in the apparatus described without departing from the spirit and scope of the invention.

I claim as my invention:

1. In combination, a hard triode comprising 15 an envelope containing a thermionic cathode, an anode and a grid arranged to emit electrons when heated, means for causing an electron flow within said envelope between said cathode and said plate, the grid 20 being interposed in the path of said flow whereby it will acquire a negative charge, a circuit external to said container including

said grid and said cathode and comprising means for insulating said grid from said cathode, and means for heating said grid 25 to temperatures at which it emits electrons, whereby an electron stream may be caused to flow from said grid to said cathode and the said negative charge controllably dissipated.

2. In combination with the grid, a plate, 30 and a filament of a hard triode, means for producing an electronic stream between said filament and said plate, said grid lying in the path taken by said stream, and additional means including a potential source for 35 heating said grid, whereby an electronic stream may be controllably produced in the reverse direction between said filament and said grid and the action of a soft triode may be simulated.

In testimony whereof, I have hereunto subscribed my name this 22nd day of June, 1920.
